DEVICE FOR THE REGENERATION OF TELEGRAPH SIGNALS

Etienne Alizon, La Celle Saint-Cloud, France, assignor to Compagnie Industrielle des Telephones, Paris, France, a corporation of France

Application July 21, 1955, Serial No. 523,555

Claims priority, application France July 26, 1954

5 Claims. (Cl. 178—70)

The object of the present invention is a device for the regeneration of telegraph signals, employing relays to the exclusion of rotating members or electronic circuits.

Regenerators of the known type employ either motor-driven cams or electronic tubes. The former have the drawback of being very expensive and delicate to maintain, while the latter generally require sources of current of very different voltages and adjusted with a high degree of precision.

The device according to the invention, which applies more particularly to signals sent out in the so-called start-stop code, comprises a time base consisting of a vibrating blade, called an "oscillolame" of the type which has been described in the French Patent No. 1,052,054 filed by applicant on March 4, 1952.

This device comprises a receiving relay of which the winding is connected to the input line of the signals, and a retransmitting relay with two opposing windings having a common point connected to one pole of a source of direct current of which the other pole is earthed, the two contacts of this re-transmitting relay being brought to two equal and opposite polarities, and its armature being connected to the signal retransmission line.

It is characterised in this, that it comprises an elastic blade oscillating with a demi-period equal to the duration of one undistorted telegraph signal, and which alternately interrupts, at a moment substantially in the theoretical middle of each signal received, the connection between earth and one or the other of the two contact pieces, each of the latter being connected, by means of a back contact of auxiliary relays, to the armature of the receiving relay, the contacts of the latter being respectively connected to the ends of the windings of the retransmitting relay, and each of the auxiliary relays being fed with current by means of one of the contacts of the elastic blade, so that, according to the position of the armature of the receiving relay, one or the other of the windings of the retransmitting relay is put in connection with earth by means of the oscillating blade, during the short moment which separates the closing of one contact of said blade, and the coming into operation of the corresponding auxiliary relay.

Attached Fig. 1 represents the circuit diagram of an example of the regenerator device according to the invention, and Fig. 2 is a diagram illustrating the operation of said device; in the latter figure the upper horizontal dash corresponding to each relay indicates that this relay is actuated and the lower dash indicates that it is in the rest position.

In Fig. 1, TR is a receiving telegraph relay, to which the signals arriving on the wire Ron are applied, and TT designates a retransmitting telegraph relay with two windings, the contacts of which are respectively connected to the positive and negative poles of a source of direct current potential, and of which the armature is connected to the wire Tron on which the signals are to be retransmitted. It will be assumed that the armatures of relay

2

TT moves to its — contact when its winding 1 is energized, and on its + contact when its winding 2 is energized.

On the other hand, Osc designates the starting coil of the oscillating blade L of an oscillolame; the half-period 5 of free oscillation of this blade is chosen equal to the duration of an undistorted telegraph signal. This blade is earthed and is associated with two contacts O₁ and O₂ in such a way that during substantially a half of its period of oscillation the contact O₁ remains open and the contact O₂ is closed, and during the next half-period 10 the contact O₁ is closed and contact O₂ open.

In the following it is assumed that each telegraph sign 15 is composed of the sequence of five signals, each having a theoretical duration of 20 milliseconds, this set of five signals being preceded by a so-called "start" signal of negative polarity and followed by a so-called "stop" signal of positive polarity, which lasts until the emission of the "start" signal of the next sign. It is also assumed that, in the drawing, all the arrows are connected to one 20 pole of a source of direct current of which the other pole is earthed.

The device according to the invention operates as follows: beginning by setting the device going by closing the 25 circuit breaker K for a brief moment, which energises relay S through the circuit: earth, interrupter K, winding 2 of relay S, battery (not shown). This relay S has the function of causing the starting of the blade of the oscillolame during the reception of the start signal of each 30 sign. The armatures of relay S come on to their make contacts and the coil Osc of the oscillolame is energised by the circuit: earth, make contact S₁, resistance r₁, contact R51, coil Osc, battery. The blade L, which was in a median rest position, the two contacts O₁ and O₂ being 35 open is pulled up, and establishes the contact O₁, which is thus earthed. Relay S is then held energised through: earth, contact O₁, contact D₁₁, rectifier C₁, armature of receiving relay TR on its + contact under the action of the positive "stop" signal, make contact S₂, winding 1 of S, 40 battery.

During this time, the winding 2 of the retransmitting 45 relay TT is energised through: earth, contact O₁, back contact D₁₁, rectifier C₁, make contact S₃, winding 2 of TT, resistance r₃, battery. The armature of relay TT is then applied on its + contact, and a positive polarity 50 of the same sign as that received on the wire Ron is transmitted on the wire Tron.

When the negative start signal preceding a telegraph 55 sign (point a, Fig. 2) arrives on the wire Ron, the relay TR rocks on its — contact and cuts off the holding circuit of the relay S (b, Fig. 2). This relay is slow releasing and its armature only falls back on its rest contacts (c, Fig. 2) at the end of a time equal to half the theoretical duration of one signal, i.e. 10 milliseconds. This 60 delay can be adjusted by means of the adjustable resistance r₂ shunting the winding 1 of S.

At this moment the winding 1 of the retransmitting 65 relay TT is energised through: earth, O₁, back contact D₁₁, rectifier C₁, armature and — contact of TR, back contact S₄, winding 1 of TT, resistance r₃, battery. The armature of relay TT rocks on its — contact and thus 70 reproduces the movement of the armature of relay TR with a delay equal to half a signal, i.e. 10 milliseconds. A negative polarity is applied to the wire Tron (d, Fig. 2).

The feed circuit of relay D₁ has been established at the moment of the release of relay S through the circuit: battery D₁, resistance r₅, back contact S₅, contact O₁, earth; however, this relay does not come effectively into operation (point e, Fig. 2) until about one millisecond later, owing to the delay due to resistance r₅. It then cuts off at D₁₁ the current supply to the winding 1 of the relay TT; the latter is therefore only energised during the

short time interval which elapses between the falling back of relay S and the engagement of relay D. It should be noted that the relay D₂ is not energised at the time of closing of contact O₁ owing to the presence of the rectifier C₂; similarly when the contact O₂ is closed, the relay D₁ will not be energised owing to the presence of the rectifier C₁.

At the time of the release of the relay S, the feed circuit Osc of the oscillolame is cut off at S₁. The blade L is then released with a certain delay due to the action of in resistance r₄, and of the rectifier C₃, and which can be adjusted by adjusting the value of the resistance r₄.

At the end of a time slightly less than 20 milliseconds, for example 19.5 milliseconds, after the opening of S₁, the blade opens the contact O₁ (f, Fig. 2) and allows the contact O₂ (G, Fig. 2) to be closed again. The closing of contact O₂ causes the energisation of the winding of the relay D₂ (h, Fig. 2), and the armature of this relay comes into the operating position at the end of about 1 millisecond. This millisecond comes about 20 milliseconds after the release of relay S which itself takes place 10 ms. after the rocking of the relay TR at the beginning of the start signal. The said millisecond is therefore situated in the theoretical middle of the first characteristic signal, following the start signal, received by the relay TR.

During this millisecond, that is to say, between the moment g when the contact O₂ is closed and the moment h when the relay D₂ rocks, the retransmission relay TT rocks on a position homologous with that occupied by the receiving relay TR.

In effect, if the armature of TR is in +, TT rocks on + through the circuit: earth, O₂, back contact D₂₁, rectifier C₂, armature and contact + of TR, back contact S₂, winding 2 of TT, resistance r₃, battery. If, on the other hand, TR is in -, TT rocks on - through: earth, O₂, back contact D₂₁, rectifier C₂, armature and contact - of TR, back contact S₄, winding 1 of TT, resistance r₃, battery.

20 milliseconds later the blade L causes the opening of the contact O₂ (i, Fig. 2), which involves, with a certain delay, the falling back of relay D₂, (j, Fig. 2), and it releases its contact O₁ (k, Fig. 2), which is closed. Relay D₁ is engaged (l, Fig. 2) by means of the back contact S₅, and its armature comes to its make contact D₁₁ at the end of a time, which as in the case of relay D₂, is of the order of one millisecond. As previously, before the relay D₁ is operated, the relay TT reproduces the position of the relay TR, through the circuit: earth, contact O₁, back contact D₁₁, rectifier C₁, + or - of TR, back contact S₂ or S₄, winding 2 or 1 of TT, resistance r₃, battery.

The same process is reproduced every time the blade of the oscillolame releases one of its two contacts, that is to say, every 20 milliseconds, in the theoretical middle of each signal of the telegraph sign received. On each occasion, the relay TT takes up a position homologous with that of relay TR and sends over the wire Tron a polarity of the same sign as that received on the wire Ron. As this relay can only change position every 20 milliseconds, the signals received are regenerated without distortion. Moreover, the registration, by the relay TT, of the polarity of each signal received can only take place, as has been seen, during a brief moment situated in the middle of this signal, the received signal can, therefore, be influenced by a considerable distortion without drawback.

Moreover, it is necessary, after the retransmission of the last signal of each sign to give a fresh pulse to the blade of the oscillolame, which is done by re-energising the starting relay S.

In order to do this, the device according to the invention comprises five counting relays R₁ to R₅, which are successively engaged, in cascade, at the time of the alternate closures of the contacts O₁ and O₂ of the oscillolame. These engagements should be effected therefore, through

the following circuits: Relay R₁: earth, O₁, make contact D₁₁, back contact R₂₁, relay R₁, battery (m, Fig. 2); relay R₂: earth, O₂, make contact D₂₁, back contact R₅₄, back contact R₃₁, relay R₂, battery (n, Fig. 2); relay R₃: earth, O₁, make contact D₁₁, make contact R₂₁, back contact R₄₁, relay R₃, battery (o, Fig. 2); relay R₄: earth, O₂, make contact D₂₁, back contact R₅₄, make contact R₃₁, relay R₄, battery (p, Fig. 2); relay R₅: earth, O₁, make contact D₁₁, make contact R₂₁, make contact R₄₁, lower winding of relay R₅, battery (q, Fig. 2). These relays are held engaged by their contacts R₁₁, R₂₂, R₃₂, R₄₂, R₅₅, and the back contact S₁.

When after the registration of the fifth sign the contact O₂ of the oscillolame is closed (r, Fig. 2) and D₂ operates (s, Fig. 2) relay S is re-engaged through: earth O₂, make contact D₂₁, make contact R₅₄, make contact R₅₂, winding of S, battery. The holding circuits of the relays R₁ to R₅ are thus cut off at S₁ and the relays R₁ to R₄ release (t, Fig. 2); relay R₅ is held operating through: earth, contact O₂, make contact D₂₁, make contact R₅₄, upper winding of 5, battery. The blade L again establishes the contact O₁ and cuts the contact O₂ (w, Fig. 2); the D₂ releases (x, Fig. 2) then R₅ (y, Fig. 2), their feed circuits being cut off at O₂.

When the sixth signal appears which follows the start signal, and which is necessarily a positive stop signal, the armature of relay TR rocks on its upper contact (if it is not already there); the relay S remains engaged owing to the circuit: battery, lower winding of S, contact S₂ in operation position, upper contact and armature of TR, rectifier C₁, back contact D₁₁, contact O₁, blade L and earth. The current supply of the relay D₁ is cut off at S₅, and its relay cannot engage (V, Fig. 2). The winding Osc of the oscillolame is re-energised through: battery, Osc back contact R₅₁, make contact S₁, earth, so that the blade L is armed in position O₁ ready to oscillate again when the start signal of the next telegraph sign is received.

All the relays are thus in the original position which they occupied at the beginning of the start signal and they are ready to receive a fresh signal.

The device according to the invention also comprises a device for counting the signals; this device consists of a counter C which is energized by means of the make contact R₅₃ of the relay 5. This counter therefore registers one pulse and one pulse only per sign contrary to what happens in certain known devices in which the counter operates under the action of all the negative signals, which does not give an exact record of the real number of the signals transmitted.

What we claim is:

1. Apparatus for regenerating telegraphic code signals, said signals being in the form of a series of signal units and each signal unit having a prevailing polarity, comprising, in combination, an input signal conductor adapted to be connected to a source of distorted telegraphic signals to be regenerated; an output signal conductor on which the regenerated undistorted telegraphic signals are to be retransmitted; a receiving relay having a winding connected to said input signal conductor, said receiving relay being responsive to said distorted telegraphic signals, and at least two contacts, said armature being adapted to move into engagement with either of the said contacts in response to said winding and in accordance with the polarity prevailing throughout the half duration of any of said signal units in the said distorted telegraphic signals; one direct current source; a retransmitting relay having at least two contacts, the last-mentioned contacts being connected to voltages of one and the other polarity, respectively, two oppositely wound windings, each winding being associated with one of said last-mentioned contacts, and an armature movable into engagement with one or the other of said last-mentioned contacts in accordance with which winding is under operation; a common end of said oppositely wound

windings being connected to one pole of said direct current source, the two other ends of said oppositely wound windings being connected to corresponding ones of said first-mentioned contacts of said receiving relay, respectively; the armature of said receiving relay being connected to the other pole of said direct current source; periodical means being provided for closing and interrupting successively the connection between said oppositely wound windings and said other pole of the direct current source, thereby to establish closing and interrupting time intervals, said closing time intervals being short relative to said interrupting time intervals, said periodical means including freely oscillating inertia means, said freely oscillating inertia means having a period of oscillation equal to the period of occurrence of said signal units; and means for synchronizing said freely oscillating inertia means with said input signals adapted to establish said closing time intervals at times corresponding to the middle of occurring signal units, whereby at said corresponding times one or the other of said oppositely wound windings of said retransmitting relay is connected for a very short time to said other pole of said direct current source in accordance with the position taken by the armature of the said receiving relay, thereby bringing the armature of said retransmitting relay into engagement with a contact of the polarity prevailing in the occurring signal unit of the received distorted telegraphic signal to be regenerated.

2. Apparatus for regenerating telegraphic code signals, said signals being in the form of a series of signal units and each signal unit having a prevailing polarity, comprising, in combination, an input signal conductor adapted to be connected to a source of distorted telegraphic signals to be regenerated; an output signal conductor on which the regenerated undistorted telegraphic signals are to be retransmitted; a receiving relay having a winding connected to said input signal conductor, said receiving relay being responsive to said distorted telegraphic signals, and at least two contacts, said armature being adapted to move into engagement with either of the said contacts in response to said winding and in accordance with the polarity prevailing throughout the half duration of any of said signal units in the said distorted telegraphic signals; one direct current source; a retransmitting relay having at least two contacts, the last-mentioned contacts being connected to voltages of one and the other polarity, respectively, two oppositely wound windings each winding being associated with one of said last-mentioned contacts, and an armature movable into engagement with one or the other of said last-mentioned contacts in accordance with which winding is under operation; a common end of said oppositely wound windings being connected to one pole of said direct current source, the two other ends of said oppositely wound windings being connected to corresponding ones of said first-mentioned contacts of said receiving relay, respectively; the armature of said receiving relay being connected to the other pole of said direct current source; periodical means being provided for closing and interrupting successively the connection between said oppositely wound windings and said other pole of the direct current source, thereby to establish closing and interrupting time intervals, said closing time intervals being short relative to said interrupting time intervals, said periodical means including at least one spaced contact and one freely oscillating member adapted to engage said contact upon movement from a free rest position, said freely oscillating member being connected to said other pole of said direct current source and said contact being connected with the armature of said receiving relay; and means for synchronizing said periodical means with said input signal, the period of said freely oscillating member being so selected that the circuit from said other pole to the one of said oppositely wound windings which is connected with the armature of said receiving relay is closed at times corresponding to the middle of an occur-

ring signal unit; said periodical means further including means energized by said other pole of said direct current source through said oscillating member and said contact for interrupting said circuit at a point situated between 5 said contact and the armature of said receiving relay at times immediately following said short closing time intervals, whereby at said corresponding times one or the other of said oppositely wound windings of said retransmitting relay is connected for a very short time to said other pole of said direct current source in accordance with the position taken by the armature of the said receiving relay, thereby bringing the armature of said retransmitting relay into engagement with a contact of the polarity prevailing in the occurring signal unit of the received distorted telegraphic signal to be regenerated.

3. Apparatus for regenerating telegraphic code signals, said signals being in the form of a series of signal units and each signal unit having a prevailing polarity, comprising, in combination, an input signal conductor adapted to be connected to a source of distorted telegraphic signals to be regenerated; an output signal conductor on which the regenerated undistorted telegraphic signals are to be retransmitted; a receiving relay having a winding connected to said input signal conductor, said receiving 20 relay being responsive to said distorted telegraphic signals, and at least two contacts, said armature being adapted to move into engagement with either of the said contacts in response to said winding and in accordance with the polarity prevailing throughout the half duration of any of 25 said signal units in the said distorted telegraphic signals; one direct current source; a retransmitting relay having at least two contacts, the last-mentioned contacts being connected to voltages of one and the other polarity, respectively, two oppositely wound windings each winding 30 being associated with one of said last-mentioned contacts, and an armature movable into engagement with one or the other of said last-mentioned contacts in accordance with which winding is under operation; a common end of said oppositely wound windings being connected to one pole 35 of said direct current source, the two other ends of said oppositely wound windings being connected to corresponding ones of said first-mentioned contacts of said receiving relay, respectively; the armature of said receiving relay being connected to the other pole of said direct current source; periodical means being provided for closing 40 and interrupting successively the connection between said oppositely wound windings and said other pole of the direct current source, thereby to establish closing and interrupting time intervals, said closing time intervals being short relative to said interrupting time intervals, said periodical means including at least two spaced fixed contacts, one freely oscillating member adapted upon oscillation to come into engagement with alternately one or 45 the other of said spaced fixed contacts, said freely oscillating member being connected to said other pole of said direct current source and each of said spaced contacts being connected to said armature of said receiving relay, whereby upon engagement of said freely oscillating member with one of said spaced contacts, one of said oppositely wound windings of said retransmitting relay is 50 connected through the armature of said receiving relay to said other pole of said direct source thereby to position the armature of said retransmitting relay in accordance with the connected winding thereof, said periodical means further comprising two slow action auxiliary relays each 55 having rest contacts, said rest contacts being inserted in the two circuits extending from said spaced contacts to the armature of said receiving relay, respectively, and said auxiliary relays having windings, each connected to said one pole of said direct current source and to one of said rest contacts, respectively, for energization by said other pole of said direct current source upon engagement of one of said spaced contacts by said freely oscillating member, the delay action of said auxiliary relays being accurately selected so that said rest contacts do not open upon 60 70 75

engagement of one of said spaced contacts by said freely oscillating member until after a predetermined short closing time interval immediately following the said engagement by said freely oscillating member, the period of said freely oscillating member being selected equal to the normal period of the distorted signal units received on said input signal conductor; and means for synchronizing said periodical means with said input signals adapted to establish said closing time intervals at times corresponding to the middle of an occurring signal unit, whereby at said corresponding times one or the other of said oppositely wound windings of said retransmitting relay is connected for a very short time to said other pole of said direct current source in accordance with the position taken by the armature of said receiving relay, thereby bringing the armature of said retransmitting relay into engagement with a contact of the polarity prevailing in the occurring signal unit of the received distorted telegraphic signal to be regenerated.

4. Apparatus as claimed in claim 3 wherein said means for synchronizing includes a starting relay for initiating free oscillations of said freely oscillating member, said starting relay being normally energized and being returned to its deenergized condition, upon reception of the first telegraphic signal by said receiving relay, with a releasing time equal to one half of the pulse width of an undistorted telegraphic signal, said starting relay having at least two rest contacts connected in circuit between said contacts of said receiving relay and said windings of said retransmitting relay for establishing said respective circuit

upon return of said starting relay to said unenergized condition thereof.

5. Apparatus as claimed in claim 4 wherein said means for synchronizing further includes a plurality of relays equal in number to the number of different elements which constitute a telegraphic character, each of said plurality of relays being connected successively in circuit with one of said auxiliary relays, respectively, to be energized sequentially upon energization of its respective auxiliary relay, said plurality of relays being connected in circuit with a rest contact of said starting relay and being maintained in the energized condition thereof by said rest contact, the last of said plurality of relays being energized having at least two windings, each of said two windings being connected to one of said spaced fixed contacts, respectively, of said oscillating means, said last relay being energized by the operation of its respective auxiliary relay upon contact of said oscillating member with one of said spaced fixed contacts and thereby partially completing an energization circuit for said starting relay, said energization circuit being completed the next time said oscillating member makes contact with the other of said spaced fixed contacts whereby said starting relay is energized and said plurality of relays is returned to the deenergized position thereof.
